UNITED STATES PATENT OFFICE.

PETER DILLON, OF LAWRENCE, MASSACHUSETTS, ASSIGNOR OF ONE-HALF
TO HENRY C. KING, OF SAME PLACE.

REFINING-ENGINE.

SPECIFICATION forming part of Letters Patent No. 621,298, dated March 14, 1899.

Application filed January 24, 1898. Serial No. 667,691. (No model.)

To all whom it may concern:

Be it known that I, PETER DILLON, of Lawrence, county of Essex, State of Massachusetts, have invented an Improvement in Refining-Engines, of which the following description, in connection with the accompanying drawings, is a specification, like letters on the drawings representing like parts.

My invention is an improvement in engines used for refining the paper stock or stuff in passing through a paper-making machine and has a twofold object in view—viz., to prevent the blades or bars and lining from being accidentally destroyed by the passage there-through of a hard substance—such as a bolt, nut, or nail—and also to prevent the working loose or out of place of the bars and filling of the plug or rotary part of the engine. In apparatus of this kind one most serious difficulty encountered is the liability of the bars and filling to become loosened from their proper positions and thereby cause disastrous injury to the machine, it being understood that enormous quantities, amounting to many tons per day, of stuff are run through an engine and at considerable pressure and also that the engine is driven at a high speed, so that there is a complexity of strains besides the centrifugal action, which all combine to dislodge the bars and filling-blocks of the plug. Accordingly I have devised the means hereinafter more fully explained, whereby each bar is held in a vise-like grip at a plurality of points throughout its length, so that it is impossible for it to have radial movement without actually tearing out the solid metal composing it, and the wooden filling-blocks between these bars are held in by an automatic clenching at their inner edges against the adjacent bars. By this provision it is absolutely impossible for my improved engine to become disrupted by radial movement of its component parts.

The details of my invention will be fully explained in the following description, and the invention itself will be more particularly defined in the claims.

In the accompanying drawings, illustrative of a preferred embodiment of my invention, Figure 1 is a central vertical longitudinal section of a refining-engine of a usual type hav-

ing the improvements constituting my invention applied thereto. Fig. 2 is a fragmentary cross-section on the line 2, Fig. 1. Fig. 3 is a transverse vertical section on the line 3 3, 55 Fig. 1. Fig. 4 is a perspective detail of the rim of one of the retaining heads or spiders. Fig. 5 is a perspective detail of the right-hand end spider, showing the means of securing the bars therein. Fig. 6 is an enlarged view of 60 the plug, looking toward the left. Fig. 7 is an enlarged detail showing the manner of securing the filling between the bars. Fig. 8 is a perspective view of one of the bars.

The general details of the engine may be 65 and are of usual construction, comprising a bed A, provided with stands a, on which are mounted a shaft a', means a² for longitudinally adjusting said shaft and its supported parts, a shell or casing a³, in the heads of 70 which the shaft is journaled and having an outlet a⁴ at one end and an inlet at a⁵ at its other end, and a driving-pulley a⁶, mounted on the shaft a'.

In passing the tons of macerated matter 75 constituting the paper-stuff through the paper-making machine, of which the herein-described engine forms one part, it is not of infrequent occurrence that nails, bolts, nuts, or other pieces of iron or unyielding substances are dislodged from the machine or dropped thereinto and carried along with the flow of stuff, causing irreparable damage when they come to the engine, being caught between the revolving plug B and the lining 80 a⁷ of the shell a³, thereby grinding and dismembering the parts thereof. With a view to obviating this disaster a settling-recess has heretofore been constructed beneath the forward or small end of the plug approximately 90 at the point marked x, Fig. 1; but in practice the stuff fills up this recess and becomes solidly packed therein by the rotating blades of the plug B, which in a very short time pack in the stuff and grind off the top surface there- 95 of even with the blades, so that the mass of indurated stuff thus gathered in the recess becomes practically integral with the lining of the engine-shell a³, so that the machine has been practically without any means for 100 catching the stray nuts, &c., mentioned. Accordingly I have offset the inlet a⁵, as shown,

and have provided a chamber a^8 , having a trap a^9 and containing a centrally-arranged outlet a^{10} , projecting upwardly within the dome a^{11} of the trap and preferably having an outwardly-flared mouth a^{12} , as clearly shown in Fig. 1, so that as the flow of stuff from the inlet a^5 enters the chamber a^8 it forms an eddy therein and the heavy foreign substances which it is desired to stop are caused to settle and remain at the bottom of the chamber, while the more liquid and lighter stuff rises to the dome a^{11} of the trap and flows out through the outlet a^{10} to the neck a^{13} of the engine. A manhole-cover a^{14} is preferably provided for inspection of the settling-chamber and a removable cap a^{15} closes an opening near the bottom of the chamber, through which the latter may be cleaned out. Also as a further precaution I prefer to form in the neck a^{13} of the engine a sand-box a^{16} , in which such lighter foreign matter as may flow over the mouth a^{12} may be caught, this sand-box a^{16} being entirely out of the influence of the plug B and therefore not subject to become packed and rendered inoperative by the rotation of said plug. A cap a^{17} is preferably provided at each side of the said box in order that the latter and the adjacent parts of the engine may be readily cleaned.

Referring now more particularly to the plug and the detailed views thereof in Figs. 2 to 8 it will be observed that I have spaced apart on the shaft a' a plurality of heads b b' b^2 , herein shown for convenience of illustration as five in number. Each of these heads or spiders is milled on its periphery or otherwise provided with a plurality of radial kerfs or notches b^3 , as clearly shown in Figs. 2 and 4 to 6, uniformly spaced apart transversely of the rim or periphery of the respective heads to snugly contain the bars b^4 , not only forming solid integral seats for the latter, but giving them lateral bracing support. The heads b' are also bored at their forward sides to provide enlargements or pockets b^5 at the bottoms of the notches b^3 , these pockets extending only part way through the web of the heads, as is clearly shown in Figs. 2 and 4. Viewing Fig. 8, it will be observed that I provide on the bar b^4 bosses or enlargements b^6 , which may be formed thereon by rolling the bar in its original manufacture, or they may be forged thereupon, or otherwise, as desired. These bosses b^6 are formed of the same size as the pockets b^5 , so that when the bars are properly seated in the notches b^3 of the respective heads each bar is immovably secured in the head simply by driving it endwise from the left hand toward the right, viewing Fig. 1, thereby driving the enlargements b^6 snugly into the pockets b^5 , as is clearly shown in Figs. 1 and 2. The head b^2 is provided at its rear peripheral edge with an annular groove or recess in which is shrunk a ring b^7 , (shown clearly in Figs. 1 and 5,) and each bar b^4 is provided at its rear end with a notch b^8 , so that as the bars are driven home, seating their bosses b^6 in the

pockets b^5 , the notches b^8 thereof simultaneously engage the ring b^7 and are thereby rigidly locked at the rear end of the plug. At 70 the forward end of the plug B the head b is provided at its forward peripheral edge with an annular recess similar to that provided at the rear edge of the head b^2 , and each bar is cut down from its outer edge at its forward end to provide a shoulder b^9 , the bottom thereof being oblique to the inner edge of the bars, as clearly shown in Fig. 8, so that when the bars have all been properly placed and driven home, as stated, a ring b^{10} is shrunk onto the 80 forward end thereof, tightly fitting the peripheral recess in the head b , and thereby engaging the shoulders b^9 and clamping all the bars b^4 permanently in place.

From the above description it is evident 85 that it is absolutely impossible that the bars should become radially dislodged in the operation of the machine without actually tearing out the solid metal of the bars. Various other expedients have been devised for accomplishing this object; but so far as I am aware none of them have proved effectual, and indeed they have served rather to weaken the bars and render them less capable of resisting the enormous strains to which they 95 are necessarily subjected.

As is well known, it is deemed necessary in this style of apparatus to place filling blocks or timbers between the bars b^4 , and there has been heretofore serious difficulty in 100 so securing these timbers that they would not work loose, especially when they should become swelled by the continuous presence of the moist stuff flowing through the engine, it having been heretofore almost impossible to 105 secure the timbers so that they would remain in place for any length of time. The serious consequences of this uncertain securing of the timbers will be plainly evident when it is borne in mind that these engines are driven 110 at considerable speed and with enormous power, so that when a timber becomes dislodged it is simply ground to pieces and wedged between the plug and the shell of the engine, necessarily causing mutual disaster 115 thereto. However, I have entirely overcome this serious difficulty simply by making the timbers b^{11} deeper than usual, as is clearly shown in Fig. 7, and driving them in so tightly that the fiber thereof has been slightly compressed between the bars, thereby causing the lower part, as soon as driven beyond the inner edges of the bars, to expand, forming lateral ridges or swells thereon, as is shown in 120 full lines, Fig. 7, the inner dotted lines of 125 said figure indicating the normal position of the wood if it had not been permitted to expand. It will be understood also that by projecting the timbers behind the bars they are also capable of receiving other or additional 130 clenching or securing means aside from the swell of the wood. Another extremely valuable effect which it is my object to take advantage of in this feature of my invention is

the further expansion of the wood as soon as it becomes soaked with the liquid stuff. The projecting portion b^{12} of the wood, being free to swell, then expands into the position shown 5 by the outer dotted lines b^{13} , Fig. 7, and thereby absolutely clenches the filling-timber beneath the bars beyond the possibility of removal.

I do not deem it necessary herein to explain 10 the construction of the lining a^7 of the engine, and I have omitted to illustrate the details thereof, inasmuch as my invention does not relate thereto, although it is obvious that the bars of the lining could be secured in the 15 same manner as the bars of the plug, if desired, this being unnecessary, however, inasmuch as the lining has no tendency to work loose.

In operation the stuff is delivered in usual 20 manner at the inlet a^5 , the stuff thence passing through the engine, where it is refined, and thence out at the outlet a^4 to the stuff-chest or machine-chest, whence it is delivered to the wire, and so on through the machine 25 in usual manner. As the stuff flows into the settling-chamber a^8 all heavy material—such as nails, coarse sand, heavy buttons, &c.—are automatically removed from the pulp or stuff, being gathered by gravity 30 in the bottom of the chamber and also stopped in their flow and precipitated by coming in contact with the flaring edges a^{12} of the pipe a^{10} , and the stuff flows through the latter into the neck a^{13} , such finer foreign matter—such 35 as sand, &c.—which would otherwise speck and spot the paper, being caught by the sand-box a^{16} , as before explained. The stuff then flows through the engine, being refined in the usual manner by being drawn out and rubbed 40 or ground down by the blades or bars b^4 of the plug in coöperation with those of the shell or lining. As the plug is rapidly rotated in performing this office, the bars b^4 are held against loosening or flying out by the engagement 45 of their bosses or enlargements b^6 with the pockets b^5 of the steel heads and the lateral support of the notches b^3 together with the engagement therewith of the retaining rings b^7 b^{10} , which all together serve to lock and 50 retain the individual bars in vise-like fashion. Also the filling or timbers b^{11} are held in firmly-clenched position behind the bars, and instead of being more liable to work loose as they become swollen by the presence of the 55 liquid stuff, as has heretofore been the case, they are thereby still more firmly and irre-movably clenched and fastened by the free swelling of their projecting inner edges, as fully explained and clearly shown in Fig. 7.

60 While I have herein described the preferred construction of my invention in its various details, I wish it understood that I am not limited to these details, inasmuch as many changes therein may be made without departing 65 from the main features and the spirit and scope of my invention. Other forms of enlargements and interlocking of the bars with

the spiders and means of locking the timbers behind the bars, as well as various changes in detail of the settling-chamber, may be re-sorted to within the terms of my invention, as hereinafter defined in the claims. 70

Having fully described my invention, what I claim as new, and desire to secure by Letters Patent, is— 75

1. In a paper-making machine, the combination with a refining-engine having a rotary plug, of an inlet thereto for the paper-stuff, and a settling-chamber between said inlet and said engine, said settling-chamber containing means to divert the direct flow of the stuff to the engine and precipitate by gravity heavy foreign materials contained in the stuff, and a sand-box in the neck of the engine but out of range of the rotating plug thereof, substantially as described. 80

2. The combination with a refining-engine, of a vertical pipe a^{10} projecting from the inlet of the engine, a drum or enlarged chamber surrounding said pipe, and a stuff-inlet pipe 90 connected to said chamber at one side thereof below the upper end of said pipe, substantially as described.

3. In a plug of a paper-stuff-refining engine, a head having a plurality of radial notches cut transversely in its periphery, each notch having at its bottom an enlarged recess extending only partially through the head, in combination with the bars of the plug fitting in said notches and provided with enlargements for said recesses, substantially as described. 95

4. In a plug of a paper-stuff-refining engine, a head having a plurality of radial notches cut transversely in its periphery, in combination with the bars of the plug adapted to fit in said notches, said bars being cut down from their outer edges to provide shoulders at their inner edges adjacent one peripheral edge of said head, and a ring secured 105 in clamping position about said head and on said shoulders, substantially as described. 110

5. In a plug of a paper-stuff-refining engine, a head having a plurality of radial notches cut transversely in its periphery, in combination with the bars of the plug adapted to fit in said notches, said bars being cut down from their outer edges to provide shoulders at their inner edges adjacent one peripheral edge of said head, said shoulders extending from their outer ends obliquely toward the inner edges of said bars, and a ring tightly secured about said head, and resting in clamping engagement on said shoulders, substantially as described. 115 120

6. A plug for a paper-stuff-refining engine, comprising a plurality of longitudinal bars and a plurality of supporting-heads therefor spaced apart and each provided with transverse peripheral notches having a width corresponding to said bars, the intermediate heads being bored out at the bottoms of their notches only part way through and on the forward sides thereof, and the bars having bosses or 130

- enlargements to fit said bored-out portions, the rear end head having a peripheral ring secured thereon across the open side of its notches, and the rear ends of the bars being notched to engage and be held by said ring, the forward ends of said bars being cut away to provide shoulders, and a ring secured peripherally on the forward end engaging said shoulders, and serving to lock said bars in place with the enlargements thereof in the bored-out portions of the intermediate heads, and the end notches thereof in engagement with the said rear ring, substantially as described.
- 15 7. In a plug for a paper-stuff-refining engine, a plurality of longitudinal bars held rigidly spaced apart radially on the plug, and

filling-timbers between said bars, said plug being freely open for the flow of water within it behind said timbers, said timbers having 20 their inner edges projecting freely behind the inner edges of said bars and clenched therebehind by the lateral swelling of the projecting edges of the timbers produced by the presence of the water within the plug, substantially as described.

In testimony whereof I have signed my name to this specification in the presence of two subscribing witnesses.

PETER DILLON.
